UNITED STATES PATENT OFFICE.

WILLIAM M. BRUCE, JR., OF SPRINGFIELD, OHIO, ASSIGNOR TO THE INTERNATIONAL AUTOMATIC TELEPHONE COMPANY, OF SPRINGFIELD, OHIO, A CORPORATION OF OHIO.

SWITCH FOR AUTOMATIC TELEPHONE SYSTEMS.

1,161,837.

Specification of Letters Patent.

Patented Nov. 30, 1915.

Application filed January 26, 1912. Serial No. 673,527.

To all whom it may concern:

Be it known that I, WILLIAM M. BRUCE, Jr., a citizen of the United States, residing at Springfield, in the county of Clark and 5 State of Ohio, have invented certain new and useful Improvements in Switches for Automatic Telephone Systems, of which the following is a specification.

My invention relates to improvements in 10 automatic telephony and especially to the construction and arrangement of the automatic switches and the circuits for the same, to effect interconnection between subscribers at an exchange without the use of operators.

15 This device relates particularly to the form of switch described in my co-pending application Ser. No. 658,492, in which a single movement or flat switch, such as used in the so-called Lattig & Goodrum system, 20 as installed at Urbana, Ohio, and elsewhere, is made to operate in connection with different banks of contacts, so as to extend its operation to a large number of subscribers, or to provide a larger number of terminal 25 connections in each switch.

This invention has also special relation to 30 switches of the selector or connector type which are operated by impulses from a subscriber's station connected thereto either directly or through the instrumentality of other so-called selector or finder switches. In the ordinary single movement or flat switch, such as used by Lattig & Goodrum, wipers were arranged to be moved step by 35 step over a series of fifty contacts or terminals and the switch was adapted to serve fifty subscribers or trunks. In the present switch I have doubled the capacity by employing two groups of fifty so that a hundred line or trunk connections are provided for in two different banks. This is typical 40 only, however, as the same arrangement might be made to apply to a larger number of banks and a fewer number of contacts in each bank, the preference being to provide 45 for one hundred lines or terminal contacts in each switch without the necessity of a vertical as well as rotary movement, the only movement in this switch being a rotary one 50 the respective wipers moving at all times in the same plane.

In the accompanying drawings: Figure 1 is a diagrammatic view showing the circuits which are preferably used for operating the

switch of my improved construction. Figs. 55 2 and 3 are similar diagrammatic views showing some of the circuits only, other circuits being omitted for the purpose of clearness. Fig. 4 is a plan view showing the mechanical construction of a switch embodying features of my invention and applicable to the system herein set forth. Fig. 5 is a plan view of the contact banks. Fig. 6 is an elevation of the same. Fig. 7 is a diagrammatic view of these terminal contacts showing the relative arrangement in the different banks. 60 65

In the switch, which I have illustrated, the respective wipers which contact with the terminals in the banks, move in the same 70 plane, and are arranged to move step by step over these bank terminals, but for the purpose of operating the switch in the decimal system, I provide for two sets of steps, to-wit: a long step and a short step and in the 75 particular case illustrated the long step is made to move the switch wipers over five terminals or contacts while the short step moves the wipers over a single contact. To do this two motor magnets are provided, one 80 for the long step and one for the short step and means are provided by which the first or long step magnet is always operated at least one step before the second magnet is operated. 85

Means are also provided by which each set of the switch wipers which engage the different bank contacts are either in or out of electrical circuit with the other mechanism depending upon whether the bank contact to 90 be selected is in one bank or the other. In the present illustration, which embodies two banks of fifty lines each as before stated, I have arranged so that the first bank, say of fifty lines, has coöperating wipers which are 95 normally in electrical connection with other necessary circuits and mechanism, and the wipers which serve the second bank of fifty lines are electrically disconnected from the said circuits and mechanism, means being 100 provided by which, when the line or terminal in the second bank is to be served or connected, the first set of wipers is electrically disconnected and the second set electrically connected to the said circuits and 105 mechanism.

Referring to Fig. 4 of the drawings, 1 represents the No. 1 or long step motor magnet

and 2 represents the No. 2 or short step motor magnet, 3 the release magnet, 4 is the bank of terminal contacts and 5 the shaft which carries the wipers which are 5 adapted to pass over said contacts. This 10 shaft 5 is provided in the usual way with a spring which holds it in the back or normal position and which is adapted to be put under tension as the shaft is revolved 15 step by step and when released to return the shaft to its normal position. The general form of the switch is the same as has been heretofore used and a brief description of its working together with the special features which I have provided will probably be sufficient for understanding it.

The shaft 5 is provided with two ratchet wheels A^5 and B^5 . The smaller ratchet wheel A^5 having a series of ten teeth and the larger wheel B^5 having preferably a series of fifty-five teeth. The small ratchet wheel A^5 is adapted to be engaged by a normally disconnected pawl a^1 pivoted to a lever a^2 and provided with an extension 25 or tail piece a^3 which normally contacts with a stop on the switch frame to hold the pawl a^1 out of engagement. The lever a^2 is connected to or is a part of the armature a^{10} of the No. 1 motor magnet and a spring 30 a^4 is provided which when the magnet is deenergized retracts the same, moves the lever a^2 to its rearward position and by causing the tail piece a^3 to engage the stop forces the pawl a^1 out of engagement with 35 the ratchet teeth of the ratchet wheel A^5 . The lever a^2 is also provided with an extension a^5 which carries a pawl tooth a^6 , which, as the lever is moved forward and reaches the limit to its forward stroke, engages a 40 tooth of a reverse ratchet a^8 formed on the wheel A^5 and thus stops the said wheel and prevents it from overthrowing. This forward movement of the lever a^2 , under the influence of the magnet, also permits the 45 pawl a^1 , by means of a spring a^7 , to be forced into engagement with the teeth of the forward ratchet a^9 and move it one notch which is sufficient to advance the wipers carried by the shaft 5 over five contacts, except in the first instance, in which 50 case, the relative position of the pawl a^1 and the first tooth of the ratchet is such that the wipers are advanced only one step onto what I call the zero contact.

55 The ratchet wheel B^5 is adapted to be engaged by a pawl b^1 on a spring pawl carrying arm b^2 pivoted to the lever b^3 on the armature b^4 of the motor magnet 2 which is also provided with a spring b^5 for retracting the armature when it is deenergized. In this case I have preferably arranged the pawl b^1 to move over one notch 60 in the ratchet wheel B^5 when the magnet is energized and to move back to its normal 65 position, and thus advance the wheel one

step, through the agency of the spring b^5 when the magnet is deenergized, being in this case a reversal of the action of the magnet 1 which advances the ratchet wheel A^5 when the magnet is energized and is returned by the spring a^4 when it is deenergized, either arrangement, however, can be used as preferable in either of the magnets, it being not an essential feature of the invention whether the magnets advance the 75 ratchet wheels when energized or when they are deenergized.

The ratchet wheel B^5 is held in its advanced position by a spring pawl b^{10} which engages the ratchet wheel at all times except when it is withdrawn by the release magnet 3 whose armature b^6 is provided with extensions b^7 and b^8 which are adapted to engage with the spring pawl b^{10} and pivoted lever b^2 when the release magnet 80 3 is energized and thus withdraw both of these pawls from the ratchet wheel to permit the said wheel, and the spring actuated shaft to return to normal position.

I have stated that the switch is preferably provided with fifty sets of contacts arranged in two banks. It will be noticed, however, that I have illustrated the bank as having fifty-seven contacts but this is due to the fact that the terminal constituting the second or lower bank are advanced five contacts ahead of the contacts in the first or upper bank and that the first contact is a normal or zero contact. This will appear more clearly hereinafter. Each 90 of the banks contain three sets of terminals and there is an additional or seventh set which might be termed the switching terminals and through which the connections between the wipers of the first and second 95 banks are connected and disconnected. This permits these banks to be divided up into groups of ten while the No. 1 motor magnet advances the wipers over five contacts only at a time, the first groups of ten in 100 the upper bank starting with the second contact of the series and the first group of ten in the lower bank starting with the first contact of the lower bank which is immediately under the sixth contact, of the upper 105 bank.

It will be obvious from the further description that the first five contacts in the lower bank and the last five contacts in the upper bank might be dispensed with as 110 they have no connections, they are only shown for symmetry in the making of the switch. It will also appear from the further description that the lower or seventh row of terminals in the banks need not 115 necessarily be in the banks, but might be placed at any point on the switch frame with a wiper to properly engage the same when the shaft is moved and that the number of contacts could be reduced to ten as only 120

ten of these contacts perform active functions.

In Fig. 1, I have shown a diagram of the circuits and apparatus for operating the switch. These circuits are in many respects similar to the usual circuits used for operating a connector switch in the Lattig & Goodrum system except as they are modified to suit and to meet the requirements of the improved features which I have added thereto and in general they embody the combination of quick and slow relays which are adapted to respond to impulses transmitted from the subscriber's station so as to first operate on the motor magnet No. 1 and give the switch the necessary long step after which by the aid of auxiliary switch mechanism the circuits are transferred to the motor magnet No. 2 and a series of short steps are given the circuits of both of the magnets being afterward opened when the switch is properly positioned with means also for shifting the circuits of the switch wipers so that only those wipers operating in connection with the bank in which the particular terminals to be selected are located will be in circuit.

In Fig. 1, MM^1 represents the long step motor magnet and MM^2 the short step motor magnet. A is the operating relay preferably having a double winding and B and C are slow relays which are adapted to be energized by the operation of the relay A and to close and hold closed certain circuits and open and hold open certain other circuits during the time that the switch is being positioned. D is the ringing relay which is also operated through relay C from the operating relay A and is held energized so long as the impulses are passing through. The various relays and magnets are shown for the most part connected on one side to ground or to grounded battery and the wires marked *g* indicate the ground connection and the wires marked *bg* indicate connection to the grounded battery. The relay A has its respective windings connected to the respective sides of the main line or talking circuit *a* and *a'* which comes into the connector switch from the subscriber's station through the preceding switches. The other ends of the respective windings are connected to the wires *g* and *bg* and thus to the opposite sides of the battery B, so that as soon as connection is made from a preceding switch to the connector switch, the operating relay A is energized, assuming the line to be closed at the subscriber's line in the usual way, the circuit passing through the respective windings of the operating relay A thus balances the line, when energized the operating relay A attracts its armature 1 and breaks the connection with back contact 2 and makes connection with front contact 3. Armature 1 is connected directly to ground by wire *g*, so that ground is thus removed from contact 2 and placed on contact 3. Contact 3 is connected by wire 4 to branch connection 5 from whence it leads through wire 6 to relay B and thence by wire *bg* to battery so that the energizing of relay A also energizes relay B. From the connecting point 5, wire 7 leads to front contact 8 on relay C while armature spring 9 immediately above said contact is connected by wire 10 to relay D which is also connected by wire *bg* to battery and ground. This circuit of relay D is normally open at contact 8. The back contact 2 of the operating relay A is connected by wire 11 to armature spring 12 of the relay B, which normally engages back contact 13. When relay B is energized, however, this armature 12 engages contact 14 which is connected by wire 15, wire connection 16 and wire 17 to relay C which is connected by wire *bg* to battery and ground, so that in case the operating relay A is deenergized and its armature moves against contact 2, the relay C would be energized over the circuit just traced providing the relay B remains energized to retain the circuit closed at contact 14. From connecting point 16 a branch 18 leads through back contact 19, armature spring 20 and wire 21 to a switch arm 22 of an auxiliary switch J. This switch arm in its normal or first position engages contact 23 which is connected by wire 24, wire connection 25 and wire 26 to MM^1 , thence by line *bg* to battery and ground, so that the closing of the circuit between armature 1 and contact 2 which will energize the relay C, will also energize the motor magnet MM^1 providing the circuit last described is closed at contact 19 and the auxiliary switch J is in its first position. Assuming the operating magnet A to have been energized by the line wires being connected to the connector switch and this is followed immediately by the energization of the relay B, if the line is momentarily broken relay A, in dropping back, would energize the slow relay C and the motor magnet MM^1 and if the line should be immediately closed giving an impulse, the operating relay would vibrate and retain relay B energized and deenergize the motor magnet MM^1 and cause it to take one step. In case a series of impulses followed in fairly rapid succession the slow relays C and B would both be held up while the motor magnet MM^1 would be operated so as to vibrate its armature in unison with the operating relay A. This will cause the motor magnet MM^1 to make as many steps as there are vibrations and cause it to select the particular group of ten in which the subscriber to be called is located. In Fig. 2 I have shown circuits directly involved in this particular part of the system with some of the other features eliminated. In this

figure S represents a subscriber's station, S¹, S², and S³ represents finder and selector switches through which the connection is made to the connector switch and to the operating relay A.

As before stated the first movement of the motor magnet MM¹ moves the wipers only on the zero contact, the second movement to the fifth contact, the third to the tenth contact, etc., also, as before stated, the contacts in the lower set or bank are moved five contacts ahead of those in the upper bank so that contact No. 50 is directly under No. 5. I also provide in the set of wipers a supplemental wiper 27 which traverses the lower row of terminal contacts in the bank, which contacts other than those immediately under terminals 5—15—25, etc., perform no particular function. These particular contacts are grounded and in each case these contacts represent an even number of steps of the first motor magnet so that in the event that the wiper 27 should stop on the second, fourth, sixth, etc., step this supplemental wiper 27 would be grounded. From the wiper 27, a wire 28 leads to a switch arm 29 on the auxiliary switch J and this switch arm normally engages contact 30 connected by wire 31 to armature 32 (of relay E) which is adapted to engage the contact 33, which is connected by wires 34 and 35 to relay G thence to battery and ground so that in the event that the wiper 27 stops on a grounded contact and the circuit of relay G is closed at contact 33 then relay G will be energized. The circuit for relay E may be traced from ground at the off-normal switch 36, by contact 37, wires 38 and 39, through various contacts shown on Fig. 1 but omitted in Fig. 2 to contact 40, armature 41, on relay C, wire 42, to relay E, battery and ground. The contact 40 is a back contact so that the circuit for relay E is closed when the relay C is deenergized and when the relay C is energized this circuit is open, the result being that the relay G can be energized only at such time as the relay E is energized and the relay C is deenergized. The relay C is energized, as before stated, when relay A is momentarily deenergized allowing contacts 1 and 2 to close on relay A with the slow relay B holding up its armature and relay C will remain energized as long as impulses are passing through A owing to the vibration of the armature of relay A; whenever the impulses cease, however, the circuit of relay C will be broken at contact 2 thus permitting the armature 41 to drop back and close the circuit for relay E at 40 providing that the circuit is closed at the off-normal switch 36 which will be true after the first movement of the main switch wiper so that after each series of impulses the relay C becomes deenergized and drops back closing the circuit

of relay E which in turn closes the circuit of relay G as before described, and in the event that the supplementary wiper 27 is resting on a grounded contact and not otherwise the relay G would be operated. Relay G controls armatures 42 and 43 which normally engage back contacts 44 and 45 in the circuits of the upper bank of wipers but are adapted when moved to their other position to engage contacts 46 and 47 in the circuits of the lower groups of wipers, these armatures themselves being connected by wires 48 and 49 to contacts 50 and 51 in the auxiliary switch J.

Relay G is provided with a locking circuit which may be traced over wires 35, 52, contact 53, armature 54 on said relay G, wire 55, to wire 38, contact 37 and grounded at off-normal switch 36, so that whenever the relay G is energized over the circuit, above described including wiper 27, it will be held energized over the last described circuit even though the wiper 27 be moved off of a grounded contact or the circuit from said wiper to the relay G be broken at the auxiliary switch J. Means are thus provided by which, whenever the auxiliary wiper 27, at the end of a series of impulses stops on a grounded contact, relay G will be energized and the circuits from the wipers relating to the upper bank will be opened and the circuits to the lower bank will be closed.

The relay E in addition to operating the armature above described also operates the escapement for the auxiliary switch and at each operation permits the arms of the auxiliary switch J to move to a different position, there being in this case preferably three positions which this switch may occupy. As soon therefore as the first set of impulses have ceased, the auxiliary switch element will be transferred from the first to the second position and switch arm 22 leaves contact 23 and stops on contact 23^a which is connected by wire 24^a to motor magnet No. 2 (MM²) thence to battery and ground so that after the first movement of the switch J, motor magnet No. 1 is cut out and motor magnet No. 2 is cut into the circuit with the operating relay A and the slow relays B and C as before described. Switch arm 29 has also passed off of contact 30 thus opening the circuit from wiper 27 to relay G and preventing relay G from being energized by any subsequent move of the wiper in case it has not been energized at the end of the first series of impulses and if it has been so energized it will remain energized as before described over the locking circuit 52, 53, 54 and 55 after the switch arm 29 moves off of the contact 30. If another series of impulses are now sent from the subscriber's station the operating relay A will be operated as before and cause motor magnet No. 2 to be vibrated which in turn

will give the main switch wipers as many steps as there are impulses. In this case, however, the steps will be short steps over one contact instead of over five contacts at each step and the individual contact in the particular group of ten desired will be selected.

Suppose now it were desired to select terminal No. 5, this number being in the first group of ten the impulse transmitted would be operated to give one impulse, this could cause one step only of the motor magnet No. 1 which, as before described, would merely be a preliminary step on the zero contact being, however, sufficient to close the off-normal switch contact at 37, at the end of this impulse the slow relay C would be deenergized which would close the circuit of relay E, the energizing of relay E would also close the circuit for relay G at contact 33 but inasmuch as wiper 27 has not stopped on a grounded contact the relay G would not be energized and the switch wipers for the upper bank would remain in circuit and those of the lower bank would be out of circuit. The energizing of relay E would cause the switch J to make one step which would thus open the circuit of relay G at contact 30 and also open the circuit of motor magnet No. 1 at contact 23 and switch motor magnet No. 2 into circuit with the operating relay A and the slow relays B and C as before described. The operator now sets his impulse transmitted to make five impulses and the wipers are caused to make five steps, bringing the series of wipers to rest on the fifth terminals in the banks, the wiper 27 will now rest on a grounded contact but inasmuch as the circuit from this wiper is open at contact 30 the relay G is unaffected and connection is made with the fifth contacts. The energizing of the slow relay C has opened the circuit for relay E at contact 40 and it is then in position to produce the second step of the auxiliary switch J and as soon as the second series of impulses cease the slow relay C, upon being deenergized will again close the circuit for relay E and cause the auxiliary switch J to take another step and thus move its arms to the third position, and this will cause the switch arms 56 and 57 to move onto the contacts 50 and 51 which are connected with the armature springs 42 and 43 and through these springs and contacts 44 and 45 by wires 58 and 59 to the switch wipers 60 and 61 of the upper bank. The auxiliary switch arms 56 and 57 are connected by wires 62 and 63 to what I term the answering relay A¹, wires 62 and 63 are also connected by wires 64 and 65 and condensers 66 and 67, wires 68 and 69 to the main wires *a* and *a*¹¹, so that the talking circuit is established directly through the condensers and the circuit above described

including the auxiliary switch arms 56 and 57 to the wipers 60 and 61 thence through the bank terminals to the called subscriber who may then be signaled in the usual way. Battery for talking purposes is fed to the calling end of the line through operating relay A and to the called end of the line through answering relay A¹.

In the event that the subscriber 51 was desired the first movement of the impulse transmitter would be to transmit two impulses. This would cause the main switch wiper at the first impulse to move one step on the zero contact and the second impulse to move one long step, that is over five contacts stopping on the fifth terminal. This being an even number of steps the wiper 27 will at the end of the first series of steps stop on a grounded contact and as the impulses cease the relay C will be deenergized and close the circuit for the relay E which will in turn close the circuit for relay G and thus switch the circuit from the upper bank of wipers to the lower bank. Energizing the relay E will also cause the auxiliary switch to move one step, as before described, which will switch the operating circuit from the motor magnet No. 1 to motor magnet No. 2 and also open the circuit from the auxiliary wiper 27 while the relay G is held up by the locking circuit so that any further movement of the wiper will not influence this connection. The subscriber now makes one impulse over the lines which causes the wipers to advance one step thus contacting with the sixth terminal which corresponds to 51 in the lower bank and inasmuch as the lower bank wipers are in circuit and the upper bank wipers and circuits are open the connection is made with the No. 51. It will be understood that this arrangement of numbering is merely arbitrary, that is, I have considered all the numbers from 1 to 50 to be in the upper bank and those from 51 to 100 to be in the lower bank. The lower bank contacts being advanced five numbers ahead of the upper bank, so that 51 rests under the 6th contact, 60 under the fifteenth, etc., then under this arrangement whenever an even number of impulses is sent at the first call it selects a number in the lower bank while an odd number of impulses at the first call selects a number in the upper bank. It is obvious that inasmuch as this numbering is merely arbitrary the first ten might be arranged in the upper bank and the next ten in the lower bank, etc. In this case the odd multiples of ten would appear in the upper bank and the even multiples of ten in the lower bank. This involves a little more complication in the wiring of the bank and the other system of having the first fifty in the upper bank and the next fifty in the lower bank requires an arbitrary

120 125 130

adjustment or arrangement of the subscriber's numbers.

It will be seen from the above that two movements of the dial or calling device are necessary to select any number in the connector switch, the first operates the No. 1 or long step motor magnet and the second operates the No. 2 or short step motor magnet. The first movement or set of impulses selects the particular group of ten in which the unit appears and the second movement selects the particular unit in that group of ten. If the group of ten to be selected requires an odd number of impulses of the No. 1 motor magnet, the numeral to be selected will be in the upper bank if the group of ten requires an even number of impulses of the first or long step motor magnet then the numeral will be in the lower bank.

It also follows that numerals representing even multiples of ten will be selected by ten steps of the No. 2 motor magnet and not by any number of steps of the No. 1 motor magnet, so that in selecting the numeral ten the first motor magnet would receive one impulse and the second motor magnet ten impulses. In selecting the numeral 50 the first motor magnet would receive nine impulses which would land it on the fortieth contact, and the second motor magnet would receive ten impulses which would land it on the fiftieth contact. In selecting the terminal 60 the No. 1 motor magnet would receive two impulses landing it on the fifth contact, but this being a grounded station it becomes a lower bank connection by reason of the lower bank wipers being brought into circuit and if followed by ten impulses of the No. 2 motor magnet stops on the fifteenth terminal or its equivalent 60 in the lower bank. The same way the selection of the seventieth would require four steps of the No. 1 motor magnet which would take it to the fifteenth contact, but this station being grounded it becomes a lower bank selection and would be equivalent to the sixtieth terminal then this followed by ten steps on the No. 2 motor magnet would move the wipers to the twenty-fifth terminal, whose equivalent in the lower bank would be terminal No. 70. The same way in selecting the one hundredth terminal, ten impulses on the No. 1 motor magnet would land on the forty-fifth terminal whose equivalent is 90 in the lower bank, this being a grounded station, the ten impulses on the No. 2 motor magnet would select the one hundredth contact in the banks.

In the above description I have included the essential features of my improved switch and its operation. In addition to these, the switch embodies the usual operating release and busy circuits, a form of which is shown in Fig. 1. Many of these circuits are also shown in Fig. 3 and omit-

ted in Fig. 2. Some of these circuits will now be described.

I have already referred to the ringing relay D which is energized by closing the contacts 8 and 9 whenever the slow relay C is 70 energized. This ringing relay D controls armature springs 70, 71 and 72. The spring 70 and its back contact 70^a is included in the circuit 62 which is connected through auxiliary switch arm 56, contact 50, wire 48 and 75 armature spring 42 to the wipers (such as 60 and 61) which select the called subscriber's terminals so that it is thus connected directly to the selected subscriber. Contact 70^b is in the generator circuit so that when 80 the ringing relay D is operated after the auxiliary switch has moved to its third or last position, ringing current will be applied to the called line. Armature spring 71 is connected to ground through wires 38 and 25 39 and the off-normal switch 33 and thus in the circuit of the auxiliary switch relay E. Contact 71^a is connected to wire 63, so that when the ringing relay D is operated the circuit for the relay E is opened and ground 90 is placed on the other side of the called subscriber's line thus completing a ringing circuit to the called subscriber. After the switch has been operated to select any terminal, the auxiliary switch is in its last position, both motor magnets will be cut out and any movement of the calling device, which will cause a series of impulses to pass over the line, will operate slow relay C and the ringing relay D, and thus cause ringing 100 current to be applied to the called line so long as the impulses are passing; in this way, ringing current will be applied by operating any number on the calling device, a short series of impulses giving a short ring and 105 a long series of impulses giving a long ring.

We will next consider the busy test and relay H, which is the busy relay. In each group of wipers, that is, the group for the upper bank of contacts and that for the 110 lower bank of contacts, there is a test wiper 73 and 73^a, which is adapted to traverse a series of contacts which are connected in multiple to the different switches in a group in the usual way. These test wipers 73, 73^a 115 are connected by wires 74 and 74^a to back and front contact 75 and 75^a on each side of armature spring 76 of relay G from said armature spring wire 77 leads to auxiliary switch arm 78 which in its last or third position rests on a grounded contact 80, so that when a line is selected ground is placed on the test contact corresponding to this line thus rendering this line busy to any other call coming in over a multiple of this line. 120 In the second position of the auxiliary switch, switch arm 78 will rest on contact 79 which is connected by wire 81 to contact 72^a on the ringing relay D. Armature spring 72 of this relay is connected through 125 130

wire 82, spring 83 (of relay C), contact 84, wire 85 to the busy relay H and to battery and ground so that if the line selected should be busy, wiper 73 would fall on a 5 grounded contact and busy relay H would be energized over the circuit just described, that is, from grounded wiper 73, wire 74, contact 75, spring 76, wire 77, auxiliary switch arm 78, contact 79, wire 81, contact 10 72^a, spring 72, wire 82, spring 83, contact 84, wire 85, relay H, battery and ground. This circuit would be held open at contact 84 so long as the relay C was energized and it would be open at contact 72^a unless the 15 relay D were energized, but relay C is de-energized after each set of impulses and relay D is de-energized when relay C has released its armature spring 9. Both of these 20 relays being slow relays and being held up while the series of impulses are passing through, so that in case the test wiper 73 should stop on a grounded contact after the first set of impulses, relay C would be de-energized and close the circuit for the busy 25 relay H before the relay D had time to drop back and open the circuit for relay H at contact 72^a. Relay H carries an armature spring 86, which is normally in circuit from wires 38 and 39 which is a part of 30 the circuit of this auxiliary switch relay E, the armature spring 71 on the relay D is also a part of this circuit for relay E being located between wires 39 and 39^a as shown in Fig. 3, so that this circuit is held open 35 so long as either relay C, D or H is energized. Since relay H becomes energized before relay D is de-energized the circuit of relay E can not be closed in case the relay H is energized by the test wiper 73 stopping 40 on a grounded contact and hence the auxiliary switch will not pass to its third position. When spring 86 is moved away from this back contact so as to break the circuit of relay E it engages a front contact 86^a connected by wire 86^b to wire 85 so that the 45 relay H is locked up by the circuit from grounded battery, wire 85, wire 86^b, contact 86^a, spring 86 wires 38^a and 38, contact 37, off-normal switch arm 36 to ground. Relay 50 H also carries an armature spring 87 adapted to engage front contact 88 which is connected by wire 89 to contact 90 in the second position of the auxiliary switch arm 55 57 which as before described and as shown in Fig. 2 is connected through wires 63 and 65 and through the condenser 67, wire 69 to the calling side of the line, thence back through the calling subscriber's telephone, line wire a¹¹, wire 68, condenser 66, wire 64, 60 winding of coil A¹, wire b₉, through battery B to ground. This armature 87 is connected to the busy tone so that when armature spring 87 is pulled up by the relay H a busy signal is sent to the calling subscriber. It 65 will be observed that the circuit for the mo-

tor magnet also passes through armature 20 on the busy relay H and hence when said relay is energized this motor magnet circuit will be broken at contact 19 (see Fig. 1), and further operation of the motor magnet would be prevented by the impulse transmitter and the operation of said transmitter by the calling operator would result only in again impressing the busy tone upon his line by energizing the relay D who thereupon hangs up and releases the switch. 70 75

The release of the switch is accomplished by opening the circuits of the respective parties at their respective stations by hanging up their receivers. The release magnet 30 of the connector switch is indicated by R and the back release for the other switch is made over the release trunk a¹². The circuit for the release magnet R may be traced as follows: from ground through armature 1 of the operating relay A, back contact 2, wire 11, armature 12, slow relay B, back contact 13, wire 91, spring 92, contact 93, (on answering relay A¹), wire 94, contact 95, off-normal spring 96, wire 97, release relay R, battery and ground, so that the release circuit will be closed whenever the relays A, A¹ and B are de-energized and this will occur when the called and calling subscribers hang up their respective receivers and thus open the respective line circuits for the called and calling subscriber. From wire 97 a branch 98 leads to a relay R¹ to battery and ground. This is the release relay for the auxiliary switch J so that the auxiliary switch J is released at the same time. 95 100 105

The back release for the other switches may be traced from trunk a¹², spring 99, contact 100, wire 101, spring 102, contact 103, to wire 91, so that the circuit for the preceding switches will be closed to ground at the same time by the de-energization of the relays A, A¹ and C. The slow relay C has a back contact 105, for its armature 110 spring 99, which is connected to trunk release a¹², this back contact is connected by wire 106 to spring 107 and grounded contact 108 on the slow relay B so that in the event that the calling subscriber should hang up 115 before the call is completed and before the called subscriber hangs up, the dropping back of armature 1 would not release the connector switch owing to the release circuit being held open at contact 93 of answering relay A¹. It would energize relay C, in the manner before described, this would be followed by the de-energizing of relay B which will permit armature spring 107 to drop back onto grounded contact 108 and 120 thus ground the trunk release a¹² through wire 106, contact 105, and spring 99 and release the preceding switches and thus freeing the calling subscriber from the connection, the connector switch would be re- 125 130

leased when the called subscriber hangs up thus closing the release circuit at 93 over the circuit heretofore described. I have provided the relay E with armature springs 5 109 and 114. Spring 114 is for supervisory purposes and is connected to a supervisory wire and when in contact with 115, which is in a branch from wire 25 in the No. 1 motor magnet circuit shows when the switch 10 has been operated. Spring 109 is connected to ground from G and is adapted to be brought into and held in engagement with contact 110 whenever relay E is energized and until the auxiliary switch J is released 15 by relay magnet R¹. This puts ground onto the contact 113 over wire 112 so that in the event that the auxiliary switch had not been completely released when the main switch returns to normal, the off-normal spring 96 20 engaging with contact 113 will again ground the release circuit for release relay R¹ and cause the auxiliary switch to be completely released.

Having thus described my invention, I 25 claim:

1. In a switch for automatic exchanges, a plurality of banks of terminal contacts, a plurality of sets of wipers one for each bank, the contacts in each of said banks being 30 arranged in groups, means for moving said wipers to the different groups, the groups of one bank being advanced in their relation to groups in the other banks, and means connected with the said banks to cause the 35 wipers pertaining to the said banks to be electrically connected or disconnected as they are moved to a group in one bank or the other bank.

2. In a connector switch, a series of groups 40 of terminals arranged in a plurality of banks, and a plurality of wipers to engage the terminals in each bank, the groups of contacts in one bank being relatively advanced over the groups of contacts in the 45 other bank, separate means for advancing said wipers by long and short steps to select a group and a contact in the group, and means connected with the respective groups to cause the wipers to be electrically 50 connected or disconnected when moved into a group pertaining to the group to be selected.

3. In a switching apparatus for automatic exchanges having a plurality of terminal 55 banks and a plurality of sets of wipers one for each bank, means for operating both sets of wipers simultaneously by long and short steps to cause them to engage terminals in the respective banks, a separate contacting 60 device moving with said wipers to engage contacts when moved by said long steps, and means operated through said auxiliary contacting device to cause one set of wipers to be electrically disconnected and the other 65 set of wipers to be electrically connected.

4. In a switching mechanism for automatic telephone exchanges, a plurality of sets of bank contacts and a plurality of sets of wipers, electrical connections from each set of wipers to a switching device, a single 70 set of connections from said switching device, and a separate contacting device moving with said wipers to cause said auxiliary switching device under predetermined conditions to connect with one set of wipers and 75 be disconnected from the other for the purpose specified.

5. In an automatic telephone exchange, a switch having a plurality of terminal banks and a plurality of sets of wipers, one set for 80 each bank, means for operating said wipers to cause them to simultaneously engage terminals in the respective banks, electrical connections from said wipers, a switching relay adapted to close one set of said connections 85 and open the other, and means connected with said wipers for energizing said relay at a predetermined movement of said wipers.

6. In an automatic switch, a series of wipers adapted to simultaneously engage 90 terminals in different banks, electrical connections from said wipers, and a switching relay for opening the electrical connections of some of said wipers and closing the connections to others, and a contacting device 95 moving with said wipers, and means for operating said relay from said contacting device at certain predetermined movements of said wipers.

7. In a switch having a plurality of sets 100 of wipers adapted to engage simultaneously different terminals arranged in different banks, the terminals of one bank being relatively advanced over the terminals of the other bank, means for advancing said wipers 105 by successive sets of steps, one set comprising long steps and the other set comprising short steps, electrical connections from said wipers to said switching relay, and means for operating said relay at the termination 110 of a certain number of predetermined long steps.

8. In an automatically operated switch having different sets of terminal contacts arranged in different banks and a set of 115 wipers for each bank, motor magnets for operating said wipers, one to produce long steps and the other to produce short steps of said wipers, means for successively switching said motor magnet into circuit to 120 operate said switch, electrical connections from said wipers to the switching relay, and means for operating said switch and relay to close one set of wipers and open the other set at the conclusion of the operation of the 125 long step motor magnet and means for preventing a further operation of said relay after the second or short step magnet has been operated.

9. In a switch having a plurality of sets 130

- of wipers adapted to engage simultaneously different terminals arranged in different banks, electrical connections from said wipers, and a switching relay for opening 5 the electrical connection from some of said wipers and closing the connection to others, a contacting device moving with said wipers, means for operating said relay from said contacting device at certain predetermined movements of said wipers, and means 10 for preventing a subsequent operation of said switching relay by a further or subsequent operation of said contacting device and before the switch is returned to normal 15 or zero position.
10. In a switch having a plurality of wipers in sets adapted to be moved simultaneously to engage different contacts, a separate contacting device moving with said 20 wipers, a switching relay adapted to open the electrical connection with some of said wipers and closing it to others, means for operating said relay from said contacting device, means for advancing said wipers by 25 successive sets of steps, one comprising long steps and the other short steps, means for operating said relay when the contacting device rests on a certain contact at the end of a predetermined number of long steps for 30 preventing the operation of said relay when the contacting device should engage the same contact when being moved by the set of short steps.
11. In a switch having two banks of fifty 35 contacts each, the contacts in one bank being advanced five spaces over the contacts of the other bank, wipers for said banks and two motor magnets, one adapted to advance said wipers by long steps and the other by short 40 steps, a switching device, electrical connections from said wipers to said switching device and a switching relay for opening the connections from one bank and closing the connections to the other, separate contacts 45 spaced to correspond with the steps or multiples thereof of the long step magnet, a movable device moving with said wipers to engage these contacts, a connection from said device to the switching relay, and means 50 for supplying current through said contacts to the switching relay when the same are engaged by said movable device after a predetermined movement of said long steps so as to switch the electrical connection from one
- set of wipers to the other as and for the 55 purpose specified.
12. In a switch for automatic telephones, terminal contacts arranged in banks and wipers for each bank, a switching device, electrical connections with one set of wipers 60 to said switching device, means for operating said switching device to disconnect some of said wipers and connect other wipers, a switching relay for operating said switching device and a circuit for said relay including a circuit closer operating simultaneously with said wipers, means for moving said wipers successively by long and short steps, and means for operating said circuit closer to energize said switching relay at the 70 termination of a predetermined number of long steps and preventing its operation when the wipers are moved by short steps.
13. In an automatic telephone exchange, having a plurality of terminal banks and a 75 plurality of wipers, one set for each bank, means for operating the wipers to cause them to engage the terminals in the respective banks, and means for connecting one set of wipers and disconnecting the other set 80 at predetermined positions of said wipers and means for releasing said switch to permit said wipers to return to normal as and for the purpose specified.
14. In an automatic telephone exchange 85 having a plurality of terminal banks and a plurality of wipers arranged in sets, one set for each bank, means for operating said wipers to cause them to operate the terminals of the respective banks consisting of 90 motor magnets, one of which advances the wipers with a long step and the other with a short step, the terminals in one bank being advanced over the terminals of the other bank a distance equal to one step of the 95 long-step motor magnet, and means at certain steps of said long-step motor magnet to establish an electrical connection and through said connection to disconnect one of said wipers and connect the other, as and 100 for the purpose specified.

In testimony whereof, I have hereunto set my hand this 20th day of January 1912.
